UNITED STATES PATENT OFFICE.

DAVID KENNEDY, OF EAST HAM, LONDON, AND ALEXANDER CRUICKSHANK ANDERSON, OF FOREST GATE, LONDON, ENGLAND.

APPARATUS FOR CLEANING BOILER TUBES, CONDENSER TUBES, AND OTHER SURFACES.

Application filed August 5, 1926. Serial No. 127,434, and in Great Britain May 4, 1925.

This invention relates to apparatus for cleaning boiler tubes or the like, in which the apparatus comprises one or more rotary flexible cutters mounted on a rotary member. The cutters may be arranged so that the centrifugal force set up by the rotation causes the cutter or cutters to fit itself or themselves into close engagement with the surface to be cleaned so that, by imparting 10 to the rotary member a motion of progression as well as of rotation, the surface is thoroughly cleaned from end to end.

When the flexible cutter is in the form of a chain the cutting surfaces may form extensions of the chain links. Or, in some cases they may comprise rollers mounted on a flexible wire rope, the outer peripheries of the rollers being milled or otherwise roughened. The cutters may be supported 20 by a cage, if so desired.

In the drawings,

Figure 1 is a side elevation of the complete device, and

Figure 2 is a front elevation of the same 25 showing the disposition of the device relative to the tubes when in use.

Figure 3 is a plan view of the device.

Figure 4 is a section on line 4—4 of Figure 1.

Figure 5 is a fragmentary view, showing 30 a side elevation on an enlarged scale, of a portion of one of the chain-like cutters.

Figure 6 is a front elevation of a portion 35 of the chain-like cutters, also on an enlarged scale.

Figure 7 is a section on line 7—7 of Figure 6, and

Figure 8 is a plan view of one of the cutting links of the cutter.

Figure 9 is a fragmentary side elevation 40 of a cutter supported by a cage, and

Figure 10 is a front elevation of the same.

Figures 11 and 12 are a side elevation and 45 a plan view respectively, of another form of chain link according to this invention.

Figure 13 is a fragmentary side elevation 50 of the form of this invention in which the cutters are in the form of milled rollers, and

Fig. 14 is an end elevation of one of the 55 rollers shown in Figure 13.

Referring to Figures 1 to 8 of the drawings, six lengths of chain *a* each a little longer in length than one quarter of the periphery of the tubes *b* to be cleaned, are

taken. The chains *a* are pivoted together at 55 one end in pairs as at *a*¹ on opposite sides of a rod *c*, their upper ends being connected to the rod *c* and their lower ends being connected to a tube *d* within which the rod *c* is enclosed. The rod *c* is channeled on opposite sides as at *c*¹ so that the chains *a* can be sunk into it for a purpose to be herein-after explained. The tube *d* is slotted as at 60 *d*¹ to accommodate the chains.

The rod *c* is rotatably mounted at its upper end in a cross-head *e* in which, however, it is prevented from rising by means of a collar *c*² secured to it, and the rod is provided with a socket *c*³ or is otherwise constructed so that a flexible or other driving 70 shaft can be attached to it in order to rotate it. Mounted across the cross-head is a worm shaft *f* provided with two worms *f*¹ which engage two worm wheels *f*². Each of these worm wheels *f*² is secured to a spindle *f*³. 75 One end of each of the spindles is screwed through a bush freely mounted on the cross-head, and their other ends are screwed through a ring which is freely mounted between flanges provided on the tube *d*. Thus, when a handle attached to the worm shaft *f* is rotated, the pinions *f*² are also rotated, thereby moving the tube *d* along the rod *c* for the purpose to be herein-after explained.

The cross-head *e* is provided with a 85 hanger *g*, and the lower end of the rod *c* is rotatably mounted in a yoke *h*, the hanger carrying wheels *g*¹ which rest upon the upper side of two of the upper tubes of the boiler, and the yoke *h* also carrying wheels 90 *h*¹ which bear on the under side of two of the lower tubes. (See Figure 2.)

The hanger *g* and the yoke *h* are provided with brackets *g*² and *h*² respectively, on which are rotatably mounted four guide 95 wheels *g*³ and *h*³ respectively, arranged to engage the adjacent surfaces of the tubes *b* with which the wheels on the hanger *g* and yoke *h* engage. Connecting the two brackets together are rods *k* having nuts *k*¹ 100 screwed on their ends whereby the whole apparatus can be adjusted in correct position for cleaning tubes. The wheels *g*¹ and *g*³, *h*¹ and *h*³ are carried in bearings *l*, adjustable by the screws *l*¹ and the nuts *l*². 105

The links of the chains *a* are provided with cutters *a*² for removing incrustation, these cutters conveniently consisting of ex-

tensions of the chain links a^3 , the cutting portion being arranged obliquely to the line of the chains, as shown in Figure 6. The chains are provided with spring wires m or 5 the like extending along them or at the back thereof so as to keep them curved to approximately the curve of the tubes to be cleaned when the chains are in the tube cleaning position.

10 Describing now the manner of using the above described apparatus, the bottom bracket h^2 is removed the rod c is moved within the tube d , by turning the said operating handle sufficiently to cause the 15 chains to lie in the channels c^1 formed in the rod, and the apparatus is then placed with the chains and the tie-rods between the brackets between two rows of tubes to be cleaned, as shown in Figure 2, whereupon 20 the bracket h^2 is refixed in position. The operating handle is now turned in the opposite direction so as to cause the portions of the chains which are pivoted together, that is, their middle portions, to move outwards 25 from the rod, thereby leaving such portions loose or free. The rod is then rotated by the flexible shaft or other suitable means at such a speed as to cause the ends of the 30 chains which are pivoted together to move outwardly due to the centrifugal action set up, so that the chains bend around or fit themselves to the tubes to be cleaned, see Figure 2, whereupon the cutters on the 35 chains effectively remove incrustation from the portions of the tubes with which they are in contact. The ends of the chains which are pivoted together are preferably loaded so as to increase the outward movement of the chains, and, therefore, the pressure with which the cutters bear against the 40 tubes. The centrifugal action imparts to the cutters not only a scraping action but a hammering action as well against the tubes.

45 When the apparatus has been advanced along the tubes up to the tube-plate, the said operating handle is rotated so as to move the tube d longitudinally of the rod c of the apparatus thereby drawing the chains flat or approximately so against the rod c , 50 in which position they can be rotated against the flat tube-plate for the purpose of removing incrustation therefrom.

55 In the construction illustrated by Figures 9 to 14, the means for drawing the chains inwardly toward the rod c may be dispensed with, the chains in such a construction being left bent outwardly from the rod.

60 In such a construction, the flexible cutters n are supported, preferably by a cage o which is secured to the revolving rod p . By mounting the cutters n in a cage, they are rendered steadier in action. The cage o is preferably of substantially U-section being secured at its base to the revolving 65 rod p by means of bolts o^1 which pass

through the base of the cage o and through the revolving rod p . The sides of the cage are cut away approximately to the normal curvature of the flexible cutters as shown in Figures 9 and 13. The outer ends of 70 the cutters are connected together at o^2 as described with reference to the above construction and the other ends thereof are fixed to the revolving rod p . For this purpose, the end link n^1 of each of the chains is 75 provided with screw holes through which pass screws n^2 which secure the link n^1 to the rod p . The chains are kept within the cage by means of pins q which project on either side of the base of one of the links 80 n and through arcuate slots o^3 cut near the edge of the cage. Two links on each chain may be provided with these pins, one near the base of the cage o , the other towards the nose thereof. The arcuate slots o^3 are 85 preferably of such size as to enable the chains to fit themselves around the tubes when in use. These pins act as check devices in order to prevent the cutters exerting undue pressure on the tubes at about 90 the centre of the chain, should this be found to occur.

95 Referring now to Figures 11 and 12, each link r of the chain is conveniently of Y-form, the cheeks r^1 of one link taking around and being pivoted to the tail leg r^2 of the next link. The cutter proper s is 100 formed diagonally across the top of the link r and, instead of the spring m being arranged at the base of the link as above described it may be arranged at the top thereof, being threaded through holes s^1 formed in the cutters proper.

105 The sides of the cage are preferably riveted together at about their centre as at t and between the two chains.

110 In a modification the cutting links may be replaced by rollers u the outer surfaces of which are milled as at u^1 , Figure 14. These rollers u are loosely threaded on a flexible wire rope v which is looped at v^1 at the nose of the cage and is secured at each end in a thimble w which is hinged to a lug x which in turn is secured to the revolving rod p . The rollers u may be loose on the wire rope 115 v in order to enable them to adapt themselves to the curvature of the tubes or the like being cleaned.

120 We claim:—

1. Apparatus for cleaning the external 120 surfaces of boiler tubes and the like, comprising means to engage and move along the outermost tubes of a pair of adjacent rows of tubes, a member rotatably supported by said means and adapted to be inserted between said rows of tubes, and flexible tube-cleaning means associated with said member and caused by the rotation of the latter member to impinge against and enter between adjacent tubes of said rows of tubes. 130

2. Apparatus according to claim 1 where-
in the tube engaging means includes a
bracket and a pair of rollers mounted on
said bracket and adapted to bear against the
5 outermost tubes of a pair of adjacent tubes.
3. Apparatus according to claim 1 where-
in the tube engaging means includes a
bracket and a roller adjustable on said
bracket in a direction parallel to the axis of
10 rotation of the rotatable member and adapt-
ed to bear against the outermost tube of one
of the adjacent rows of tubes.
4. Apparatus for cleaning the external
surfaces of boiler tubes and the like, com-
15 prising a member adapted to be inserted be-
tween a pair of opposed rows of tubes, a pair
of brackets in which the opposite ends of
said member are rotatably supported, a plu-
20 rality of flexible tube cleaning members car-
ried by said member and caused by the ro-
tation of said first-named member to im-
pinge against and enter between adjacent
25 tubes of said rows of tubes, means connect-
ing said brackets and permitting adjustment of
said brackets toward and away from one an-
other, and means carried by said brackets
30 to bear against the outermost tubes of said
opposed rows of tubes.
5. Apparatus according to claim 1 where-
35 in the tube-cleaning means comprises a plu-
rality of flexible members extending along
the rotatable member in parallelism to the
axis of said rotatable member and in stag-
40 gered relation to one another and caused
by the rotation of said rotatable member, to
alternately impinge against and enter be-
tween a pair of adjacent tubes of said rows
45 of tubes.
6. Apparatus for cleaning the exterior
surfaces of boiler tubes, condenser tubes and
the like, comprising a member for insertion
50 between a pair of opposed rows of tubes and
capable of rotation between and movement
longitudinally of said tubes, a second mem-
ber associated with said first-named member
55 and movable in the direction of the length
of the latter, and chain-like tube-cleaning
means associated with said members, each
of said chain-like means being caused by the
60 rotation of said first-named members to im-
pinge against and enter between adjacent
tubes of said opposed rows of tubes and be-
ing drawn out of position to engage said
65 tubes by the relative longitudinal movement
of said first-named members.
7. Apparatus according to claim 6 where-
in the first-named member is of tubular form
and has slots extending parallel to its axis,
the second-named member is mounted within
70 said tubular member and has depressions ex-
- tending parallel to its axis and in alignment
with the slots in the first-named member, and
each of the chain-like cleaning means has
one of its ends connected to said first-
named member adjacent one end of one of 65
said slots and its other end connected to the
opposite end of the aligned depression of the
second-named member.
8. Apparatus for cleaning the external
surfaces of boiler tubes and the like compris-
70 ing a member for insertion between two rows
of tubes and rotatable between and movable
longitudinally of said tubes, means carried by
said member and engageable with one of said
tubes for supporting said member between 75
the rows of tubes to be cleaned, flexible means
associated with said first-named member and
projectile by the rotation of said member
into engagement with and between a pair of
80 tubes of each of said rows of tubes, and re-
silient means associated with said flexible
means and normally maintaining said flexi-
ble means in curvilinear form.
9. Apparatus for cleaning boiler tubes,
condenser tubes, and other surfaces compris-
85 ing a rotary member, chain-like cleaning
means secured thereto and a resilient sup-
port associated with said cleaning means and
adapted to maintain said cleaning means
90 curved to the curvature of the surfaces to be
cleaned when the cleaning means are in po-
sition to engage said surfaces.
10. Apparatus for cleaning the outside of
boiler tubes, condenser tubes, and other sur-
faces comprising an upper bracket and a 95
lower bracket, means connecting said brack-
ets and on which said brackets are relatively
adjustable to adjust the apparatus in the cor-
rect position for cleaning tubes, a rotary
100 member mounted between said brackets and
flexible cleaning means secured to said rotary
member.
11. Apparatus for cleaning boiler tubes,
condenser tubes, and other surfaces compris-
105 ing an upper bracket and a lower bracket, tie
rods between said brackets and on which
said brackets are relatively adjustable to ad-
just the apparatus for cleaning tubes, a
110 rotary member carried by said upper and
lower brackets chain-like cleaning means se-
cured to said rotary member and a spring
wire extending along said cleaning means
to maintain said cleaning means curved to
115 conform to the curvature of the tubes to be
cleaned when the cleaning means are in the
cleaning position.

In testimony whereof we have signed our
names to this specification.

DAVID KENNEDY.

ALEXANDER CRUICKSHANK ANDERSON.
